UNITED STATES PATENT OFFICE.

FRANK L. HARMON, OF BEVERLY, MASSACHUSETTS, ASSIGNOR TO SINGER MANUFACTURING COMPANY, OF ELIZABETH, NEW JERSEY, A CORPORATION OF NEW JERSEY.

EYELETING-MACHINE.

1,262,584.

Specification of Letters Patent.

Patented Apr. 9, 1918.

Application filed May 9, 1914. Serial No. 837,595.

To all whom it may concern:

Be it known that I, FRANK L. HARMON, a citizen of the United States, and resident of Beverly, county of Essex, Commonwealth of Massachusetts, have invented an Improvement in Eyeletting-Machines, of which the following description, in connection with the accompanying drawings, is a specification, like characters on the drawings representing like parts in each of the several views.

This invention relates to eyeletting machines of that type wherein the eyelets are automatically inserted in the material and clenched with an automatic feed of the material, to space the eyelets between successive eyeletting operations. A prime object of the invention is to provide a machine of this type adapted to insert and clinch eyelets at a much higher speed than has heretofore been feasible, and to so dispose the working parts that they are exceptionally convenient for control by the operator, being all disposed at one side of the material support. To these ends one important feature of the invention consists in a multiple eyeletting machine of the material feeding type that is selectively duplex or quadruplex in its action, all the active work of eyeletting being done from one side of the material. In accordance with this feature of the invention the machine may be duplex to enable two pieces of material lying side by side and edge to edge to be eyeleted at the same time, or it may be used duplex to enable two eyelets along the line of feed in one piece of material to be eyeleted at each operation, or it may be used quadruplex combining these two duplex features. I believe the present machine is the first duplex or quadruplex eyeletter that is capable of eyeletting two pieces of material lying side by side with their edges toward each other, and also the first machine of the material feeding type wherein a plurality of eyelets are inserted and clenched at each eyeletting operation from one side of the material. A further feature of the invention consists in a novel construction of horn or material support shaped so that the two curved sides of a shoe quarter may be eyeleted at the same time while they are placed with their edges toward each other thereon. A further feature of the invention has to do with adjusting means for variably spacing the two

punches arranged in the line of feed, according to the distance desired between the eyelets; this feature in its preferred and more complete embodiment having also provision whereby the same adjusting means that spaces the punches is also adapted to vary the stroke of the material feeding means correspondingly so that a single adjustment is all that is necessary to vary the eyelet spacing in this type of machine. The above and other objects and features of the invention will be better understood from the following detailed description taken in connection with the accompanying drawings and will be thereafter pointed out in the appended claims.

Referring to the drawings:

Figure 1 is a side elevation of a machine constructed in accordance with my invention;

Fig. 2 is a sectional detail showing a telescopic punch and set mechanism that is preferably employed in connection with my invention;

Fig. 3 is a plan view of the machine; and

Fig. 4 is an end view of the immediate working parts and material support looking from the left in Fig. 1, the operating mechanism being omitted for the sake of clearness.

At the front of the base support 1 is a bracket block 2 constituting a work supporting member, it for this purpose being extended back as a horn 3. This work supporting horn and the operative surface plates adjustable thereon as presently described are curved upward from the end of the horn as seen at 4 to permit two pieces of material such as a pair of curved quarters of a shoe to lie thereon with their edges toward each other in parallelism as later more fully explained. The curved surface of horn 3 has slidably fitted thereto correspondingly curved plates 5, 6, the plate 6 being shown as superposed on the plate 5, the plate 5 being extended beyond the plate 6 where it is formed with outer clenching surfaces 7 and the plate 6 having its extremity formed with inner clenching surfaces 8. These two plates have upstanding lugs 9, 10, at their respective ends bearing journal pins connected with links 11, 12 respectively which in turn are connected with the mountings of the pairs of relatively adjustable punches as presently described

through pins 13, 14 connected with the respective punch mountings and pivotally connected to said links as seen at 15. A suitable presser foot formed as a spring plate 16 5 extends from the block 2 to the end of the horn with long wide slots 17 at its outer portion to accommodate the lateral punch movements to be presently described. The outer end of the horn is also shown as equipped 10 with a thin plate 18 carried by a bracket fixed to the horn and extending in over the slide plates 5 and 6, being suitably apertured to uncover the clenching surfaces of said plates as seen at 18^a and serving to support 15 the material so that it will not be moved by frictional engagement with said plates alone. The base 1 is equipped at a distance back from the material support with a transverse slide way 19 in which is fitted a slide 20 20 which extends across the base and is equipped with journal bearings for the operating levers to be now described. This slide has spaced apart upstanding lugs 21 provided with journal bearings to serve as 25 the fulcrum of a lever 22 which extends back from this fulcrum point with a roller 23 at its rear end engaging a wide peripheral cam 24 fixed on a shaft 25 which is the drive shaft of the machine journaled in suitable 30 bearings in uprights 26 at the rear of the base and having thereon a driving pulley 27 with a suitable stop clutch 28. The lever 22 has at its front end a head 29 in which are fitted a pair of telescopically combined punch and set mechanisms 30, 31 35 disposed in parallelism endwise of the lever. The lever 22 has its outer end portion equipped with a lateral projection 32 adapted to serve as a slide support for a slide 40 block 33 fitted thereonto which bears a head 34 equipped with a second pair of telescopically combined punch and set mechanisms 35, 36 arranged in parallelism with the first mentioned pair 30, 31 and similarly spaced 45 apart endwise of the lever. Means is provided whereby the pair of punch and set mechanisms 35, 36 may be variably spaced from the pair 30, 31 and for this purpose I provide an adjusting pin 37 having threaded 50 engagement through the lever 22 and also through the slide block 33, with a knurled operating head 38 at its outer end. The adjustment of this pin serves not only to space the pairs of punch and set mechanisms apart 55 variably as required but it also determines the extent of lateral operative movement of the pairs of punches for feeding the material and spacing the eyelets. For the purpose of effecting this lateral spacing movement a striker 39 for engaging the head of the adjusting pin 37, is mounted on the end of a lever 40 fulcrumed at 41 to a rear portion of the base support with a roller 42 at its inner end in position to engage a lateral 60 cam 43 fixed on shaft 25. The outer portion 65 of this lever is acted on by a spring 44 fixed at 45 to an extension of the base so as to hold the roller 42 against the cam 43. Thus the extent that the lever 22 carrying the punch and set mechanisms along with the 70 slide 20 will be moved laterally by the lever 40 is determined by the in and out adjustment of the pin 37 as threaded in said lever, since the more said pin is adjusted out toward the striker head 39, the less lost motion of the lever there will be and hence the greater lateral shifting movement of the lever for spacing the eyelets. The threads on the pin 37 are so arranged that those engaging the slide block 33 will move it laterally away from the lever 22 by the same amount that the adjustment of pin 37 toward the head 39 lengthens the operative or spacing stroke. To effect this the threads 37^a on the portion of said pin engaging the 80 slide block 33 are of coarser pitch than those 37^b on the back part of the pin engaging the lever 22, the pitch ratio being two to one; for example assuming the threads 37^a to be twenty-two to the inch, the threads 37^b 90 will be 44 to the inch. A suitable lock nut and washer 46 may be provided for securing the threaded pin 37 against turning when properly adjusted, by its locking action against the block 33. The pins 13, 14 which 95 as before described are connected to operate the slide plates 5, 6, are fixed respectively to the lever 22 and to the block 33 and hence are adapted to move said plates so as to keep the clenching surfaces 7, 8, underneath and 100 in alignment with the respective sets of the two pairs throughout their range of adjustment toward and from each other, as well as causing said clenching surfaces and the punch blocks associated therewith on the 105 plates 5, 6 to be moved with the punch and set mechanisms in their lateral movement for feeding the material and spacing the eyelets. A tension spring 47 has its ends engaged with the slide 20 at 48 and with a post 49 110 upstanding from the base and moves the slide over to the limit of its movement toward the striker 39 as far as permitted by a suitable stop device 50 on the base to engage therewith. All of the punch and set 115 mechanisms are alike and each consists in a hollow set 51 threaded for adjustment in the head which carries it with a lock nut 52 to secure it in adjusted position. In this set is slidably fitted a tubular punch 53 which 120 normally projects therefrom being held in such projected position by a spring 54 secured at one end to the head and engaged at its other end with a collar 55 threaded on a rear extension of the punch, this collar 125 being interlocked on the punch between nuts 56 and 57, the latter of which serves as a gage to determine the extent of normal forward projection of the punch. Means is provided whereby the punches are held posi- 130

tively projected from the sets and moved downward for the punching operation and for this purpose I provide a lever 58 having a head 59 with a face wide enough to engage 5 all the punches in punching position, this lever being fulcrumed at 60 to an upright 61 extending up from the base 1 with a roll 62 at its rear portion engaging a peripheral cam 63 fixed on shaft 25, this roll being 10 held in engagement with said cam by a coil spring 64 secured at one end to the extremity of the lever 58 and at its other end to the base as seen at 65. Another suitable spring 66 is mounted in position to hold the roll 23 15 of lever 22 against its cam 24.

It may now be understood that in use, starting from the initial position shown in the drawings the two pairs of punch and set mechanisms 30, 31 and 35, 36 are moved 20 downward under the action of the rising portions 24^a, 63^a of peripheral cams 24, 63 which thus cause all the punches and sets to be moved down together with the punches held positively projected from the sets 59 25 by lever 58. As this occurs, each punch takes off an eyelet *e* from the end of suitable eyelet raceways indicated at 67 the eyelets sliding back on the punches so that their flanges rest against the ends of the sets. As 30 the downward punch movement continues, the punches are forced through the material against the punch block surfaces at the ends of plates 7, 8, which punch block surfaces, it will be understood in the present embodiment, are within the annular grooves which 35 constitute the clenching surfaces. Thereupon the lever 58 is moved back by its spring as permitted by a receding portion 63^b of its controlling cam, so that the punches are now 40 only held yieldingly forward by the springs 54. Thereupon the sets are moved farther down to slide the eyelets off the punches through the material and to clench them in the punched holes under the action of a further 45 raised portion 24^b of the cam controlling lever 22. After this occurs the lateral cam 43 is in position to act on the roller 42 swinging the striker head 39 against the head of the bolt 37 and shifting the slide 20 50 bearing the punch and set mechanisms together laterally for spacing the eyelets the required distance according to the adjustment of threaded bolt 37 as previously explained. It will be understood that this lateral 55 shifting movement of the punch and set mechanisms occurs while they are engaged with the clenched eyelets in the two pieces of material, and that the plates 5, 6 bearing the respective punch block and 60 clenching surfaces partake of this lateral shifting movement sliding on the circularly curved slide ways 4 of the horn 3. Thereupon the punches and sets are withdrawn clear of the material this being permitted 65 by raised portions 24^c, 63^c of their respective

cams, when a lowered portion of cam 43 permits lateral return of the slide 20 bearing the punches and sets back to initial position.

The two pieces of material *m*, *m'*, adapted to be operated on simultaneously as described, may be fed into the machine gaged laterally against a central rib 68 upstanding from the plate 18, there being a suitable receiving mouth formed by a flaring end 69 of the presser plate 16 with a correspondingly flared member oppositely fixed to the end of the horn. It will be understood that the curve of the horn as indicated at 4, and of the material support slide plates 5, 6 fitted thereto, will depend on the kind of material to be eyeleted, for example, if eyelets are to be placed in the edges of two normally flat pieces of material the horn and slide plates would of course form a plane surface. The form shown is about the degree of curve adapted for holding the two sides or quarters of a low shoe with their edges in parallelism against the guide rib 68 as required for properly positioning the lines of eyelets. It will be understood that for high shoes the curve might be considerably higher than shown, but in all instances with a correctly formed curve or incline the two edges of a pair of material pieces such as shoe quarters and uppers may be made to extend in substantial parallelism for the eyeleting operation.

It will be understood that when it is desired to use the machine duplex instead of quadruplex as described, the pair of punch and set mechanism carried by the head 34 may be dismantled so that there will be only one punch operating on each piece of material, or the inner punch and set mechanisms 30, 35 of each pair may be dismantled so that two eyelets will be inserted and clenched on one piece of material at each operation. While I have herein shown my invention as carried out with telescopically combined punch and set mechanisms, it is to be understood that in certain broader aspects having to do particularly with plural eyeleting at each operation either on a single piece of material with a feed and spacing of the material, or on two pieces of material set side by side and edge to edge, the use of the telescopic punch and set combination while desirable is not essential nor is the invention in these respects limited thereto. Therefore where the expression "punch and set mechanism" or the like occurs in the appended claims unless particularly so stated it is not to be understood as being limited to a telescopically combined punch and set. Where the expression "eyeleting operating" or the like occurs in the claims it is to be understood as referring to the punching of the holes, the inserting of the eyelets therein, and the clenching of the eye-

lets. I am aware that each of these features as well as various other features of the invention may be employed advantageously in other relations than those shown and I 5 therefore desire the present embodiment to be considered as illustrative and not restrictive, referring rather to the appended claims to indicate the scope of the invention.

Having described my invention, what I 10 claim as new and desire to secure by Letters Patent is:

1. A multiple eyeleting, comprising a material support, a plurality of punch and set mechanisms each composed of a relatively 15 movable punch and set the punch formed to remove material to receive an eyelet, co-operative with said support for performing a plurality of eyeleting operations on a single piece of material at one operative 20 movement, and wholly from the same side of said support, and means operative in timed relation to the eyeleting operations for feeding the material to space the eyelets, said punch and set mechanisms being mounted 25 in spaced apart relation along the line of feed.

2. An eyeleting machine, comprising a material support, a plurality of punch and set mechanisms each composed of a material 30 removing punch and a set disposed in alignment and spaced apart along the line of material feed wholly on one side of said support, means for operating such punch and set mechanisms, means for feeding the 35 material to space the eyelets, and mechanism for varying the spacing of the eyelets, including means for variably spacing said punch and set mechanisms along the line of material feed.

40 3. An eyeleting machine, comprising a material support, a plurality of punch and set mechanisms each composed of a material removing punch and a set mounted on the same side of said support in alignment and 45 spaced apart along the line of material feed, means for operating said mechanisms for the eyeleting operations, and means operative in timed relation to the eyeleting operations for feeding the material to space the eyelets.

50 4. An eyeleting machine, comprising a material support, a plurality of punch and set mechanisms each composed of a material removing punch and a set mounted on the same side of said support spaced apart along 55 the line of material feed, means for operating said mechanisms for performing a plurality of eyeleting operations at once on the same piece of material, and means operative in timed relation to the eyeleting operations 60 for moving the punches of said mechanisms laterally to feed the material and space the eyelets.

65 5. An eyeleting machine, comprising a material support, a plurality of punch and set mechanisms mounted on the same side

of said support spaced apart along the line of material feed, means for operating said mechanisms for performing a plurality of eyeleting operations at once on the same piece of material, means for moving the 70 punches of said mechanisms laterally between eyeleting operations to feed the material and space the eyelets, and means for varying the spacing of the eyelets.

6. An eyeleting machine, comprising a 75 material support, a plurality of punch and set mechanisms mounted on the same side of said support spaced apart along the line of material feed, means for operating said mechanisms for performing a plurality of 80 eyeleting operations at once on the same piece of material, means for moving the punches of said mechanisms laterally between eyeleting operations to feed the material and space the eyelets, and an adjusting device connected and arranged to vary the lateral spacing movement of the punches, and also the distance between the punches of the respective punch and set mechanisms 85 by the same adjustment.

7. In an eyeleting machine, comprising a material support, a plurality of eyeleting mechanisms mounted to coöperate therewith and spaced apart along the line of material feed, means for moving an operative part 95 of said mechanisms along the line of material feed while engaged with the material for feeding the same and spacing the eyelets, and means varying the spacing of the eyelets, said means consisting in a member 100 having differential threads on different parts thereof, engageable with said lateral moving means, and operable to vary the lateral movement of said operative parts, and also the distance therebetween.

105 8. An eyeleting machine, comprising a material support, a plurality of punch and set mechanisms mounted for coöperation with said support and spaced apart along the line of material feed, means for moving the punches of said mechanisms laterally while engaged in the material for spacing the eyelets, and means for varying the spacing of the eyelets, said means consisting in a threaded pin having differential threads 110 on different parts thereof engageable with the mountings of the respective punch and set mechanisms to vary their distance apart, said pin being also coöperative with the means for moving the punches laterally for 115 varying the extent of their movement in accordance with its adjustment.

9. An eyeleting machine, comprising material supporting means, a plurality of eyeleting mechanisms each composed of a relatively movable punch and set mounted and movable in operative relation thereto, and spaced apart along the line of material feed, and means for moving an operative portion 125 of said mechanisms while engaged with the 130

material in a straight line to feed the material and space the eyelets.

10. An eyeleting machine, comprising a material support, a plurality of punch and set mechanisms mounted and movable in operative relation thereto and spaced apart along the line of material feed, and means for moving the punch elements of said mechanisms laterally in a straight line while 5 engaged in the material for feeding the same and spacing the eyelets.

11. An eyeleting machine, comprising material supporting means formed with an intermediate upstanding rib to guide two 15 pieces of material side by side and edge to edge, and a plurality of eyeleting mechanisms mounted in operative relation to said supporting means for setting a line of eyelets in both simultaneously.

20. 12. An eyeleting machine, comprising a material support formed with an intermediate upstanding rib and adapted to guide two pieces of material side by side and edge to edge, a plurality of eyeleting mechanisms 25 mounted and movable in operative relation thereto, and means for feeding the material to set a line of eyelets in each material piece.

13. An eyeleting machine, comprising a material support formed with an intermediate 30 upstanding rib and adapted to guide two pieces of material side by side and edge to edge, and two telescopically combined punch and set mechanisms mounted in spaced apart relation along the line of material feed and 35 movable to form eyelet lines along the edges of the respective material pieces, and means for feeding the material.

14. An eyeleting machine, comprising a material support formed and adapted to 40 guide two pieces of material side by side and edge to edge, two telescopically combined punch and set mechanisms having a common mounting in spaced apart relation along the line of material feed and movable in operative 45 relation to said support, and means for moving an operative part of said punch and set mechanisms laterally to space the eyelets.

15. An eyeleting machine, comprising a material support formed and adapted to 50 guide two pieces of material side by side and edge to edge for feeding, said support having a surface gradually changing in direction in an easy curve along the line of feed whereby material pieces such as a pair of shoe quarters may be set and fed with their edges in parallelism, and a plurality of eyeleting mechanisms mounted and movable in position to set lines of eyelets in two 55 material pieces on said support.

16. An eyeleting machine, comprising a material support formed with an intermediate upstanding rib, and adapted to receive two pieces of material side by side and edge to 65 edge, the receiving surface of said support

being formed on a gradual, substantially continuous curve adapted to permit two material pieces such as a pair of shoe quarters to be fed thereon with their edges substantially in parallelism, a plurality of punch and set mechanisms mounted and movable in operative relation to said support to set eyelets in a line in each of two material pieces, and means for feeding the material between eyeleting operations to space the 75 eyelets.

17. An eyeleting machine, comprising a material support having slidably fitted thereon a plurality of members each equipped with a punch block and clenching surface, a plurality of eyeleting mechanisms mounted and movable in co-operative relation with said punch blocks and clenching surfaces, means for moving said eyeleting mechanisms laterally of said support, and 80 connections for simultaneously moving the members bearing said punch blocks and clenching surfaces therewith.

18. An eyeleting machine, comprising a material support, a plurality of members 90 each equipped with a punch block and a clenching surface slidably fitted thereon, a plurality of punch and set mechanisms mounted in operative relation to said support, said punch and set mechanisms being 95 mounted for adjustment as a unit toward and from each other and also for movement together and as a unit laterally for feeding the material, and connections from the respective punch and set mechanisms to the 100 respective members bearing said punch blocks and clenching surfaces whereby said members partake of the adjustments and movements of said mechanisms.

19. A multiple eyeleting machine, comprising a material support formed and adapted to guide two pieces of material side by side and edge to edge, a plurality of eyeleting mechanisms each composed of a material removing punch and a set mounted 105 transversely of the direction of material feed and movable in operative relation to said support to set a line of eyelets in each of two material pieces thereon, and a second set of eyeleting mechanisms mounted in 110 spaced apart relation along the line of material feed adjacent the first named mechanisms for doubling the eyeleting operations on each material piece at each operative movement.

20. A multiple eyeleting machine, comprising a material support formed and adapted to guide two material pieces side by side and edge to edge, a pair of punch and set mechanisms each composed of a 115 material removing punch and a set mounted transversely of the direction of material feed and movable in operative relation thereto for producing eyelet lines in both material pieces at once, a second pair of punch and 120 set mechanisms each composed of a material removing punch and a set mounted transversely of the direction of material feed and movable in operative relation thereto for producing eyelet lines in both material pieces at once.

set mechanisms mounted side by side with the first named pair and spaced therefrom, along the line of material feed, means for operating all of said punch and set mechanisms together, and means for feeding the material between eyeleting operations to space the eyelets.

21. A multiple eyeleting machine, comprising a material support formed and adapted to guide two material pieces side by side and edge to edge, a pair of punch and set mechanisms mounted transversely of the direction of material feed and movable in operative relation thereto to set eyelets in a line in both material pieces at once, a second pair of punch and set mechanisms mounted side by side with the first named pair and spaced therefrom along the line of material feed, means for operating all of said punch and set mechanisms together, and means for moving operative elements of said punch and set mechanisms laterally while engaged with the material to space the eyelets.

22. A multiple eyeleting machine, comprising a material support formed and adapted to guide two material pieces side by side and edge to edge, a pair of telescopically combined punch and set mechanisms mounted and movable in operative relation thereto to set eyelets in a line in both material pieces at once, a second pair of telescopically combined punch and set mechanisms mounted side by side with the first named pair and spaced therefrom, means for operating all of said punch and set mechanisms together, and means for moving punch elements of said punch and set mechanisms laterally while in the material for feeding the same and spacing the eyelets. 40

In testimony whereof, I have signed my name to this specification, in the presence of two subscribing witnesses.

FRANK L. HARMON.
